DESIGN.

J. A. BUSH.
GAME BOARD.

No. 27,191.

Patented June 8, 1897.

FIG 1

FIG 2

UNITED STATES PATENT OFFICE.

JAMES A. BUSH, OF PORT GIBSON, MISSISSIPPI.

DESIGN FOR A GAME-BOARD.

SPECIFICATION forming part of Design No. 27,191, dated June 8, 1897.

Application filed April 6, 1897. Serial No. 631,028. Term of patent 7 years.

To all whom it may concern:

Be it known that I, JAMES A. BUSH, of Port Gibson, in the county of Claiborne and State of Mississippi, have invented and produced a 5 new and original Design for a Game-Board, of which the following is a full, clear, and exact description.

Reference is to be had to the accompanying drawings, forming a part of this specification, 10 in which similar characters of reference indicate corresponding parts in both the figures.

Figure 1 is a plan view of the design, and Fig. 2 is a view showing the sectional appearance of the design on the line 2-2 of Fig. 1. 15 The design in its entirety is as follows: It is produced on a base A, which is elongate, and its side edges are contracted and run with compound curves, respectively, into the rounding end edges of the base. On the base 20 is a vertical edge wall B, following the contour of the edge of the base and inclosing a series of inner walls C, in turn corresponding to the walls B. The several walls or partitions form elongate inclosures communicating with 25 each other by openings G in the wall C, the openings and adjacent walls being out of registry with each other. There is a central fig-

ure contracted at its middle within the inner wall C and spaced therefrom and having its defining-lines in conformity with the walls B 30 and C. Inclosures D appear at the ends of the central figure C. The tapering inner ends of the inclosures D appear covered, as at E. These inner ends are separated by a solid figure F, contracted at its middle. 35

The leading feature of my design consists of the puzzle with the endless inclosures contracted or curved inward toward each other at their sides and merging into broad rounding ends, the several inclosures communicat- 40 ing with each other at points out of registry.

A further leading feature consists in the puzzle with the endless inclosures and the central figure, within which is a solid figure contracted at its middle and the ends of which 45 have enlarged rounded inclosures.

I claim—

The design for a game-board substantially as herein shown and described.

JAMES A. BUSH.
